UNITED STATES PATENT OFFICE.

MARSHALL REA, OF PHILADELPHIA, PENNSYLVANIA, ASSIGNOR OF ONE-HALF TO
IGNACE EBENAU, OF NEW YORK, N. Y.

NECKTIE-FASTENER.

1,178,458.

Specification of Letters Patent.

Patented Apr. 4, 1916.

Application filed May 14, 1915. Serial No. 28,154.

To all whom it may concern:

Be it known that I, MARSHALL REA, a citizen of the United States, residing at Philadelphia, in the county of Philadelphia and State of Pennsylvania, have invented new and useful Improvements in Necktie-Fasteners, of which the following is a specification.

The invention relates to a necktie fastener, and more particularly to the class of bow tie clasps or fasteners.

The primary object of the invention is the provision of a clasp or fastener of this character wherein an ordinary bow tie which resembles the hand tied bow is conveniently fastened in position at the gap in the fold of the shirt collar of the turn-over style with despatch, thereby obviating the fastening of the tie to the head of a collar button in the usual manner, or otherwise securing it in position, thus relieving the user of the troublesome manipulation of the tie in securing the same, and the untidy appearance thereof when engaged upon the collar button in the ordinary well-known manner.

Another object of the invention is the provision of a clasp or fastener of this character wherein the collar is firmly held fast at the front thereof when the tie is in wearing position, so as to avoid any excessive opening of the gap between the folded over portion of the said collar, and thereby eliminating the pinching of the neck of the wearer resultant therefrom.

A further object of the invention is the provision of a clasp or fastener of this character wherein the bow tie will be firmly held in its adjusted position at the point of and overlapping the gap between the folded over portion of the collar at the front thereof so as to avoid the sagging of the tie at either side of the gap, or displacement thereof when worn, and also will eliminate the spreading of the collar or the working of the overlapped front ends thereof fastened to the collar button, which ordinarily results in an untidy appearance to the wearer.

A still further object of the invention is the provision of a clasp or fastener of this character which is novel in form to assure the proper positioning and securing of both the tie and collar without any inconvenience to the user.

A still further object of the invention is the provision of a clasp or fastener of this

character which is extremely simple in construction, readily and easily applied to a bow tie without in any manner disfiguring the shape thereof, thoroughly reliable and efficient in its purpose, strong, durable, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawing:—Figure 1 is a perspective view of a collar showing a bow tie fastened in position in accordance with the invention. Fig. 2 is a front elevation of the clasp removed from the tie. Fig. 3 is a rear elevation thereof. Fig. 4 is a longitudinal sectional view showing the clip or fastener in position for securing the tie in place. Fig. 5 is a top plan view showing the clasp or fastener open and removed from the tie.

Similar reference characters indicate corresponding parts throughout the several views in the drawing.

Referring to the drawing in detail, A designates generally a shirt collar, which in this instance is of the folded over style, and B a bow tie, which resembles the hand tied bow, and is of the usual well-known construction, having fastened therein the clasp or fastener hereinafter fully described.

The clasp or fastener comprises a frame C including a pair of spaced parallel side or cheek plates 10 which are united to a curved or arcuate shaped back plate 11 through the medium of narrow connecting web portions 12 which are formed medially thereof and space the side or cheek plates 10 from the said back plate of the frame. Arranged between the side or cheek plates 10 is a pair of clamping jaws 13, the inner ends of which are formed with pivots 14 which are journaled in the side or cheek plates 10 contiguous to a central stud 15 which is fastened in the side or cheek plates 10, and has coiled about the same a tension spring 16, the respective ends 17 of which play against the clamping jaws 13 for working at opposite sides of the said stud to normally hold the same away from the back plate 11 or in open position so that the folded or turned over portion of the collar A can be engaged therebetween so that on the closing of the jaws 13 the frame will be firmly clamped to the free

ends of the folded or turned over portion of the said collar, the jaws 13 being closed in a manner presently described.

The clamping jaws 13 are reversely curved with respect to the curvature of the plate 11, and also are formed close to their pivoted inner ends with abrupt swells or bights 18 for a purpose presently described.

Pivoted within the frame C outside of the points of pivotal connection of the jaws 13 therein are eccentric levers 19 which are formed at their inner ends with in-turned lips or tongues 20 which frictionally slide upon the swells or bights 18 which constitute cams in the clamping jaws 13 so that they will be suddenly and quickly moved to clamping position on pressing inwardly upon the eccentric levers 19 and also to assure a wide range of opening of the clamping jaws or the separation thereof from the back plate 11 with slight outward movement of the said eccentric levers 19 for the unfastening of the clasp or fastener. The eccentric levers 19 have their pivots 21 journaled in the side or cheek plates 10 of the frame C to permit free swinging movement thereof.

The clamping jaws 13 and the eccentric levers 19 are formed with apertures 22 to provide holes for thread stitches whereby the clasp or fastener can be secured in the tie without necessitating the wrapping of thread about the said jaws and levers and thereby presenting unsightly stitching upon the wings of the tie B when the clasp or fastener is mounted therein.

The clasp or fastener is built into the tie B with the back plate 11 exposed centrally at the rear thereof, while the jaws 13 and eccentric levers 19 are concealed within the inner wings of the bow tie B, and the thread stitching is carried through the apertures 22 in both the jaws and eccentric levers so that the wings of the tie are what is commonly known as tacked thereto, and thereby eliminating undue stitching for the fastening of the clasp or fastener within the tie.

In the application of the tie the eccentric levers 19 are pulled outwardly, thereby separating the clamping jaws 13 from the back plate 11, as these jaws are acted upon by the spring 16 which causes the opening of the jaws, and now the tie may be conveniently applied to the collar with despatch by merely inserting the back plate in the gap between the ends of the folded or turned over portion of the collar A and sliding it to the position desired. The free ends of the folded or turned-over portion at the gap of the collar engage in the spaces 23 provided between the side of the cheek plates 10 and the back plate 11 of the frame at opposite sides of the web portions 12 spacing the side of the cheek plates from the said back plate 11 of the frame. When the tie B has been properly

positioned relative to the collar A the eccentric levers 19 are pushed inwardly by pressing upon the wings at opposite sides of the knot of the tie B, causing the lips or tongues 20 to act upon the cam swells or bights 18 in the clamping jaws 13, thereby forcing the same against the resistance of the spring 16 in relation to the back plate 11 for the clamping of the free ends of the folded or turned over portion of the collar A therebetween, and thereby securely fastening the tie in proper position and also firmly holding or fastening the collar at the front thereof so as to prevent the spreading of such collar or the excessive opening or closing of the gap in the front thereof.

When the eccentric levers 19 are pressed inwardly for the fastening of the tie in position they will cause the wings of the tie to assume a tidy and neat appearance relatively close to the collar without resultant stiffness in the appearance of the tie so that it will closely resemble the hand tied bow.

From the foregoing description, taken in connection with the accompanying drawing, the construction and manner of use of the device will be clearly understood, and therefore a more extended explanation has been omitted.

What is claimed is:—

1. The combination with a bow tie, of a fastener comprising a frame supporting the tie and forming an arcuate shaped stationary back plate and spaced cheeks, a pair of clamping jaws pivoted in the frame between the cheeks thereof, and levers pivoted in the frame and adapted to act on the jaws to move the same in clamping relation to the back plate of the frame.

2. The combination with a bow tie, of a fastener comprising a frame supporting the tie and forming an arcuate shaped stationary back plate and spaced cheeks, a pair of clamping jaws pivoted in the frame between the cheeks thereof, levers pivoted in the frame and adapted to act on the jaws to move the same in clamping relation to the back plate of the frame, and resilient means for opening the jaws on releasing the levers.

3. The combination with a bow tie, of a fastener supporting the same and comprising stationary and movable clamping members, means concealed within the tie for actuating the movable clamping members to bring the same in locking position relative to the stationary member, and means for separating the movable clamping members from the back plate when released from the stationary member.

4. The combination with a bow tie, of a fastener supporting the same and comprising stationary and movable clamping members, means concealed within the tie for actuating the movable clamping members to bring the same in locking position relative

to the stationary member, means for separating the movable clamping members from the back plate when released from the stationary member, the said movable members and lever being concealed within the tie.

5. The combination with a bow tie, of a frame having cheeks concealed within the tie and a back plate without the same, clamping members movably mounted within the cheeks and coacting with the back plate for clamping action, means within the tie and

supported by the frame for acting upon the said members to move the same in clamping position, and means to separate the members from the back plate when the members are 15 freed.

In testimony whereof I affix my signature in presence of two witnesses.
